UNITED STATES PATENT OFFICE.

PETER DARMSTADT, WILHELM STEGMANN, AND VALENTIN WEIL, OF FECHENHEIM, NEAR FRANKFORT-ON-THE-MAIN, GERMANY, ASSIGNEES TO THE FIRM DRAHT-INDUSTRIE PETER DARMSTADT & CO., G. M. B. H., OF FRANKFORT-ON-THE-MAIN, GERMANY.

DRAWING RING FOR WIRE-DRAWING MACHINES.

Application filed January 11, 1928, Serial No. 245,835, and in Germany September 22, 1927.

It is well known to provide the rotating drawing rolls or rollers of wire drawing machines with separate drawing rings loosely fitted thereon which feed the wire by reason of the friction between the ring and the drawing roll or roller, and are adapted to compensate for the lengthening which occurs during the drawing operation, by reason of the reduction in cross section of the wire, between 5 the drawing dies, in such a manner that they always adjust themselves automatically to the correct speed of rotation and peripheral speed corresponding to the lengthening of wire occurring at any particular time. The 10 drawing dies, in such a manner that they always adjust themselves automatically to the correct speed of rotation and peripheral speed corresponding to the lengthening of wire occurring at any particular time. The 15 drawing rings hitherto used for this purpose were of comparatively large cross section and were rigid. Consequently the friction between the ring and the drawing roll or roller was too low and attempts were made to increase this by lubricating the contact surfaces with a suitable adhesive (lubricant of great toughness). This method fulfills its purpose when the speed of drawing is not too high, but has not been found very satisfactory. In 20 consequence of the increase in drawing speed which it has been attempted to obtain in recent times, particularly for the purpose of greater economy, the drawing members are considerably heated, that is to say the rotary 25 drawing rolls or rollers and the loosely fitted drawing ring, so that the lubricant is rendered fluid to such an extent that it is no longer possible for the drawing rings to operate properly at high drawing speeds.

According to the invention there are used for the purpose of increasing the friction between the drawing rings and the drawing rolls or rollers, elastic drawing rings, that is to say the cross section of these rings is so 30 dimensioned that during the drawing operation they are capable of being deformed under the action of the pulling tension of the wire and consequently the surface with which they bear against the drawing rolls or rollers 35 is increased.

In the accompanying drawing are illus-

trated elastic drawing rings in accordance with the invention, the various figures being diagrammatic illustrations.

Figure 1 is an elastic drawing ring according to the invention, in the normal position, and

Figure 2 shows two such elastic rings which are exposed to the pulling tension of the wire during the drawing operation.

In order that the invention may be readily understood the proportions have been exaggerated in the drawing.

The drawing ring *c*, according to the invention, is made deformable and elastic, and in the normal or unstrained condition (Figure 1) bears only with a small contact surface on its drawing roll or roller *b*. As soon, however, as it comes under the action of the variable pulling tension of the wire to be drawn, it is deformed and the contact or bearing surface becomes larger in proportion to the increase of the pulling tension of the wire (Figure 2) and consequently the friction between the drawing ring and the drawing roll or roller is proportionately increased.

By means of the new elastic drawing rings, whilst avoiding any separate adhesive lubricating means, the object of the frictional drive and the feeding of the wire is effected in a simple and very effective manner whilst constantly compensating for increases in length, even at high drawing speeds.

On the periphery the rings may be provided with one or more ribs serving as guide tracks or paths for the wire passed over them. At high drawing speeds they also prevent the undesirable cutting action of the wire as also the breakage thereof which frequently occurs with the constructions used hitherto.

We wish it to be understood that the illustrations in the drawings are diagrammatic only and that various refinements may be made within the scope of the appended claim. A continuous ring has been shown freely fitted upon a driving roll. By "continuous ring" we mean a ring that has no gaps or

open cross-cut spaces in its periphery, and by "freely fitted" we refer only to a ring whose rotation about the drum is unlimited.

We claim:

- 5 In combination with a drawing roller of a wire-drawing machine, an elastic continuous ring fitted freely on such roller, said ring being adapted to contact with the wire along only a portion of its periphery, the ring thus
- 10 being deformable by the tension of the wire

during the drawing operation to vary the area of the bearing surface between the ring and the roller in accordance with variations in the tension of the wire.

In witness whereof we have hereunto set 15
our hands.

PETER DARMSTADT.
